CLAIM

The ornamental design for a flossing apparatus, as shown and described.

DESCRIPTION

FIG. 1 is a perspective view of a flossing apparatus, showing a first embodiment of my new design;

FIG. 2 is an enlarged top plan view of FIG. 1, the bottom plan view being a mirror image thereof;

FIG. 3 is a front elevational view of FIG. 1, the rear elevational view being a mirror image thereof;

FIG. 4 is a left-side elevational view of FIG. 1, the right-side elevational view being a mirror image thereof;

FIG. 5 is a cross-sectional view thereof, taken along line 5--5 of FIG. 4;

FIG. 6 is a cross-sectional view thereof, taken along line 6--6 of FIG. 4;

FIG. 7 is a perspective view of a second embodiment thereof;

FIG. 8 is an enlarged top plan view of FIG. 7, the bottom plan view being a mirror image thereof;

FIG. 9 is a front elevational view of FIG. 7, the rear elevational view being a mirror image thereof;

FIG. 10 is a left-side elevational view of FIG. 7, the right-side elevational view being a mirror image thereof;

FIG. 11 is a cross-sectional view thereof, taken along line 11-11 of FIG. 10; and,

FIG. 12 is a cross-sectional view thereof, taken along line 12-12 of FIG. 10.

The broken lines represent portions of the flossing apparatus that form no part of the claimed design. The second embodiment illustrates the flossing apparatus of the first embodiment but with two transparent handles.
